ROTARY MACHINE HAVING IMPROVED OIL CIRCULATION MEANS

David M. Smith, Hermosa Beach, Calif., assignor to Emsco Derrick & Equipment Company, Los Angeles, Calif., a corporation of California

Original application June 3, 1931, Serial No. 541,771. Divided and this application February 13, 1933, Serial No. 656,604

22 Claims. (Cl. 255—23)

My invention relates to rotary machines of the character employed in drilling oil wells by the so-called rotary system and this application is a division of my application entitled Oil enclosed rotary, Serial No. 541,771, filed June 3, 1931.

In the oil well drilling industry a rotary machine is placed on the derrick floor of a well. The drill pipe extends through a rotary table 10 of the rotary machine and carries a bit at its lower end. In the present common form of rotary machine the rotary table has a bevel or ring gear which is driven by a pinion mounted on a pinion shaft, which pinion shaft is journaled in bearings of the rotary machine. A sprocket is secured to the outer end of the pinion shaft, and this sprocket is driven from a draw works of the derrick by a chain and sprocket arrangement. When the rotary machine is operated, the rotary table is rotated and the drill pipe and bit are thus caused to rotate, the bit digging away the bottom of the hole in order to deepen same.

Oil wells today are being drilled to exceedingly great depths, necessitating larger and heavier drilling apparatus which consequently materially increases the already tremendous strains to which rotary machines are subjected during the drilling of an oil well. As a result, the working parts of rotary machines have been made more and more rugged and massive in order that these strains and stresses may be withstood. Furthermore, it has and is becoming quite necessary to provide suitable and ample lubrication for the working or wearing parts of the rotary machines in order to minimize friction and to reduce wear.

It is an object of my present invention to provide a rotary machine in which all the working parts are completely enclosed and constantly lubricated.

It is another object of my invention to provide an oil enclosed rotary machine in which the bevel ring gear of the rotary table, the pinion, and the main table thrust bearing included in the rotary machine are all operable in a common bath of oil.

It is one of the important objects of my invention to provide a rotary machine in which the main table bearing is constantly bathed by a stream or flow of oil which passes through the bearing. This oil is so circulated that when it is delivered to the main table bearing, it is relatively cool and relatively clean.

It is a further object to provide a rotary ma-

chine of the character referred to in the foregoing paragraph in which there is an oil reservoir to which the oil flows after lubricating and cooling the main table bearing wherein any sediment may settle to the bottom of the oil reservoir and thus permit only the clean oil to be circulated through the parts to be lubricated.

It is another object of my invention to provide in a rotary machine of the type described an oil reservoir in which a body of lubricant is maintained, and in which the pinion of the rotary machine is rotatable, the pinion being operated to carry or splash the lubricant to the rotary table ring gear meshing therewith.

It is a still further object of my invention to provide in a rotary machine, as described in the above paragraph, means for delivering a flow of lubricant from the ring gear to the rotary table bearing, and means for delivering lubricant from the rotary table bearing back into the oil reservoir.

Another unique feature of my present invention is that the main table bearing is of a tapered roller bearing type having the roller bearings so arranged that the axes of the rollers are disposed at an angle to the horizontal so that the faces of the rollers lie in a plane at a steep angle from horizontal in order to facilitate the centering of the table on the base.

In the following detailed description of my invention other objects and important advantages of the invention will be pointed out. For the purpose of illustrating the details of my invention, I have selected what I consider at the present time to be the preferred form of my invention. It should be understood that I do not wish to be limited to this particular form of my invention, since I understand my invention to be susceptible of embodiment in various forms.

Referring to the drawings which accompany this specification,

Fig. 1 is an elevational view, partly sectioned, of a rotary machine incorporating the features of my invention.

Fig. 2 is a plan view of Fig. 1, Fig. 2 being partly in section.

Fig. 3 is an enlarged fragmentary sectional view showing the manner in which the lubricant is delivered from the ring gear to the means for directing the lubricant to the main bearing.

Fig. 4 is a fragmentary view illustrating the manner in which the lubricant passes through the main bearing and is delivered therefrom to the oil or lubricant reservoir.

Referring to the drawings in detail and particularly to Figs. 1 and 2, I have illustrated a rotary machine which includes a base casting 11 provided with suitable skid constructions 12, which in this form of the invention are integral with the other parts of the base 11. Formed integrally with a horizontal wall 13 from which the skids 12 depend, and adjacent one end thereof, is a vertically extending annular wall 16 which is of a diameter substantially equal to the width of the horizontal wall 13. Formed also integrally with the wall 13 is a vertically extending annular wall 22 which is of smaller diameter than the annular wall 16 and cooperates with this wall 16 and the horizontal wall 13 to form an oil or lubricant reservoir 23. The wall 22 extends upwardly from the wall 13 a comparatively short distance relative to the wall 16 and is of considerably greater thickness for the purpose of providing an upper horizontal face 25 for the support of a rotary table bearing generally designated by the numeral 26. The inner annular surface 27 of the wall 22 defines an opening which extends through the horizontal wall 13, this opening being concentric with the vertically extending annular wall 16.

The bearing 26 is preferably of the tapered roller type and comprises a lower stationary race 30, tapered rollers 31 spaced by a roller retainer 32 and an upper rotatable race 33. The lower race 30 is prevented from rotation relative to the base 12 by a series of dowel pins, one of which is shown at 34 in Fig. 1, which project upwardly from the surface 25 of the wall 22 and extend into depressions formed in the lower face of the race 30, as shown. The bearing 26 is preferably designed so that the axes of rotation of the tapered rollers 31 are positioned at approximately 45° from the vertical or from the horizontal so that the upper faces of these rollers lie in a plane at a relatively steep angle from the horizontal to facilitate the centering of a rotary table 40 which is journaled by the bearing 26. This rotary table 40 includes a vertically extending cylindrical wall 41 of such an external diameter as to engage the inner surface 27 of the wall 22 in a running fit, this wall 41 terminating upwardly in an annular shoulder 42 which provides a downwardly facing horizontal surface 43 against which the race 33 abuts and to which this race is secured by suitable means.

Formed integrally with the wall 41 of the table 40 is a horizontally extending flange or body portion forming the table top 44 of the rotary table 40. The peripheral part 45 of the table top 44 is positioned adjacent the upper edge of the annular wall 16 and forms a relatively tight joint to prevent the leakage of lubricant from the oil reservoir 23. Secured to the under side of the table top 44 and secured thereto is a ring gear 46 provided with downwardly facing bevel teeth 47. The ring gear 46 has an internal diameter slightly greater than the outer diameter of the bearing 26 and has an external diameter slightly less than the internal diameter of the annular wall 16.

For the purpose of operating the rotary table 40 I provide a pinion 48 having bevel teeth 49 adapted to engage the teeth 47 of the ring gear 46. This pinion, as shown in Fig. 1, is positioned within the annular wall 16 and the lower portion thereof extends into the oil reservoir 23 to a point below the lubricant level therein. This pinion 48 is secured to the inner end of a pinion shaft 50. The pinion shaft 50 is supported by a pair

of pinion shaft bearings 51 which includes suitable housings for supporting them, and the outer end thereof has a sprocket 52 secured thereto by means of which the rotary machine may be operated.

For the purpose of holding the table 40 in place and preventing same from being inadvertently raised from position, I provide a hold-down bearing 54 which is supported between a lower wall 55 of the base 11 and a retaining member 56 10 which is secured to the lower end of the cylindrical wall 41 of the rotary table 40. This hold-down bearing 54 prevents the rotary table 40 from being raised, while any weight on the rotary table during the operation thereof is carried by the 15 main table bearing 26.

Secured to the inner surface of the wall 16, as by screws or other means, are a number of downwardly sloping drip pans 80 which constitute a means for delivering lubricant to the main bearing 26. These drip pans 80 are positioned directly below the ring gear 46 inclining downwardly and inwardly, as shown. The drip pans 80 are shown to be three in number and are positioned in spaced relationship around the annular wall 25 16 and above the oil or lubricant reservoir 23, but it is of course apparent that the number of these pans is immaterial. Upon an inspection of Fig. 4, it will be seen that the inner part of the drip pans 80 projects above outer portions of 30 the main table bearing 26.

As shown best in Fig. 4, the numeral 81 designates an oil throw-off means which is adapted to return lubricating fluid from the bearing 26 to the oil reservoir 23. This throw-off means 81 includes a narrow vertically extending annular flange 82 formed on the inner annular part of the bearing supporting face 25 of the wall 22. Formed on the outer surface of the cylindrical wall 41 of the rotary table 40 at a point immediately above the flange 82 and directly below the bearing retainer 32, is a plurality of annular grooves 83 which forms a plurality of relatively sharp edges, as shown. The grooves 83 are provided for the purpose of preventing lubricating fluid from finding its way downwardly between the wall 41 and the flange 82 of the wall 23 by reason of the fact that these grooves collect any fluid which might be flowing downwardly on the surface of the cylindrical wall 41 and the same 50 is thrown outwardly above the flange 82 by centrifugal force as the rotary table revolves. Provided in spaced relationship in the upper surface 25 of the wall 22 is a plurality of downwardly and outwardly sloping drain channels 85. These 55 drain channels 85 extend from the base of the flange 82 to the outer periphery of the annular wall 22 and are provided for the purpose of delivering lubricating fluid thrown from the groove 83 and flowing from the bearing 26 back into the 60 oil reservoir 23.

The operation of the rotary machine and particularly the operation of the parts which constitute the essence of my invention are as follows: Upon rotation of the pinion shaft 50, the 65 pinion 48, due to its engagement with the teeth 47 of the ring gear 46, causes the rotary table 40 to be rotated. Due to the fact that the lower part of the pinion 48 is submerged in the body of lubricating fluid contained in the reservoir 23, it 70 picks up a quantity of lubricant and carries it into contact with the teeth 47 of the ring gear 46. A portion of this lubricant, which is oil, ordinarily, adhering to the teeth 47 of the ring gear, is thrown outwardly by centrifugal force against 75

the inner surface of the wall 16, and in passing downwardly by gravity is collected by the drip pans and flows down these drip pans to be delivered directly to the annular bearing 26, as disclosed by the arrows C in Figs. 3 and 4. The lubricating fluid delivered to the roller bearing 26 by the drip pans 80 eventually finds its way to the lower portion of the bearing and from there flows downwardly and outwardly through the drain channels 85 and into the reservoir 23, as indicated by the arrows E of Fig. 4. A portion of the lubricating oil passing inwardly through the bearing 26 will adhere or tend to adhere to the cylindrical wall 41, and will flow downwardly over the surface thereof until reaching the throw-off groove means 83 wherein the lubricating oil will collect and will be thrown outwardly by centrifugal force over and above the flange 82 and into the drain channels 85, as indicated by the arrows F of Fig. 4.

It will be seen that the oil circulating means of my invention delivers a continuous flow or stream of lubricant to the main bearing 26. This lubricant has a very valuable washing and cooling action on the bearing and effectively cools the bearing and washes the bearing surfaces clean, as well as supplying the necessary lubrication to enable its efficient operation. The lubricant chamber 23 provides a settling space wherein any particles or sediment carried in the oil may settle out. It will be understood that in relatively large castings there will be small fragments of metal breaking loose or scale breaking loose from the walls, as well as particles of sand which are carried in the pores of the metal, this sand being deposited in the surfaces or pores of the metal during the casting operation. Due to the continuous flow of lubricant over the main bearing 26, none of these foreign particles will remain in the bearing due to the effective washing action.

I claim as my invention:

1. In a rotary machine of the type employed in the drilling of oil wells, the combination of: a base; a table above said base, said table and base cooperating to provide an annular oil chamber; a main bearing supported by said base adjacent said oil chamber and in open communication therewith; means for driving said rotary table, including a pinion, and a ring gear mounted on said rotary table within said chamber, said pinion being adapted to deliver oil to said ring gear; and means for directing the oil from said ring gear inwardly above the oil level of said chamber to said main bearings.

2. In a rotary machine of the type employed in the drilling of oil wells, the combination of: a base; a rotary table above said base, said base and table cooperating to provide a lubricant chamber; a cylindrical wall depending from said table; a bearing supported by said base at a higher level than said lubricant chamber and surrounding said cylindrical wall, said bearing supporting said rotary table; means supplying said bearing with lubricant from a level above the bearing; and drain means extending downwardly from said bearing for delivering the lubricant from the inner part of said bearing downwardly to said lubricant chamber.

3. In a rotary machine of the type employed in the drilling of oil wells, the combination of: a base; a rotary table above said base, said base and table cooperating to provide a lubricant chamber; a cylindrical wall depending from said table; a bearing supported by said base and surrounding said cylindrical wall, said bearing

supporting said rotary table; means whereby said bearing is supplied with lubricant; and drain means situated below said bearing for delivering the lubricant from the inner part of said bearing to said lubricant chamber.

4. In a rotary machine of the type employed in the drilling of oil wells, the combination of: a base; a rotary table above said base, said base and table cooperating to provide a lubricant chamber; a cylindrical wall depending from said table; a bearing supported by said base and surrounding said cylindrical wall, said bearing supporting said rotary table; means whereby said bearing is supplied with lubricant; drain means for delivering the lubricant from the inner part of said bearing to said lubricant chamber; and means on said cylindrical wall adapted to throw the lubricant outwardly therefrom so that the lubricant will flow into said drain means.

5. In a rotary machine of the type employed in the drilling of oil wells, the combination of: a base; a rotary table above said base, said base and table cooperating to provide a lubricant chamber; a cylindrical wall depending from said table; a bearing supported by said base and surrounding said cylindrical wall, said bearing supporting said rotary table; means whereby said bearing is supplied with lubricant; drain means situated below said bearing for delivering the lubricant from the inner part of said bearing to said lubricant chamber; and means on said cylindrical wall adapted to throw the lubricant outwardly therefrom so that the lubricant will flow into said drain means.

6. In a rotary machine of the type employed in the drilling of oil wells, the combination of: a base having an upstanding wall; a rotary table cooperating with said upstanding wall for providing a lubricant chamber; a shelf inwardly of said upstanding wall and adjacent said chamber; a bearing on said shelf for rotatably supporting said rotary table; drive means for driving said table including a ring gear secured to said table and a pinion gear, both of which are within said chamber, said pinion gear delivering lubricant to said ring gear; and means above the oil level in the lubricant chamber for directing lubricant dropping from said ring gear inwardly to said bearing.

7. In a rotary machine of the type employed in drilling oil wells, the combination of: a base having an annular oil channel and an annular shelf inwardly of said oil channel; a bearing supported on said shelf; a table supported on said bearing, said table cooperating with said base to form a closed chamber in which said annular oil channel, said shelf, and said bearing are located; a ring gear secured to said table and situated in said chamber above said oil channel; means for supplying oil to said ring gear, said oil dropping downwardly in said chamber from the teeth thereof; and means for intercepting said oil falling through said chamber and delivering same to said bearing.

8. In a rotary machine of the type employed in drilling oil wells, the combination of: a base having an annular oil channel and an annular shelf inwardly of said oil channel; a bearing supported on said shelf; a table supported on said bearing, said table cooperating with said base to form a closed chamber in which said annular oil channel, said shelf, and said bearing are located; a ring gear secured to said table and situated in said chamber above said oil channel; means for supplying oil to said ring gear, said

- oil dropping downwardly in said chamber from the teeth thereof; and a pan situated in said chamber below said ring gear for intercepting said oil falling through said chamber and delivering same to said bearing.
5. In a rotary machine of the type employed in the drilling of oil wells, the combination of: a base having an annular oil channel; a rotary table above said base and cooperating therewith to form a closed chamber in which said oil channel is located; a bearing in said chamber adjacent said oil channel for rotatably supporting said table; a ring gear on said table within said chamber; means for supplying said ring gear with oil, said oil falling from said ring gear; and means for intercepting said oil falling from said ring gear and delivering same to said bearing, said oil then flowing from said bearing to said oil channel.
10. In a rotary machine of the type employed in the drilling of oil wells, the combination of: a base having an annular oil channel; a rotary table above said base and cooperating therewith to form a closed chamber in which said oil channel is located; a bearing in said chamber adjacent said oil channel for rotatably supporting said table; a ring gear on said table within said chamber; means for supplying said ring gear with oil, said oil falling from said ring gear; and
15. a pan in said chamber below said ring gear for intercepting said oil falling from said ring gear and delivering same to said bearing, said oil then flowing from said bearing to said oil channel.
20. 10. In a rotary machine of the type employed in the drilling of oil wells, the combination of: a base having an annular oil channel; a rotary table above said base and cooperating therewith to form a closed chamber in which said oil channel is located; a bearing in said chamber adjacent said oil channel for rotatably supporting said table; a ring gear on said table within said chamber; means for supplying said ring gear with oil, said oil falling from said ring gear; and
25. 30. a pan in said chamber below said ring gear for intercepting said oil falling from said ring gear and delivering same to said bearing, said oil then flowing from said bearing to said oil channel.
11. In a rotary machine of the type employed in the drilling of oil wells, the combination of: a base having an annular oil channel; a rotary table above said base and cooperating therewith to form a closed chamber in which said oil channel is located; a bearing in said chamber adjacent said oil channel for rotatably supporting said table; a ring gear on said table within said chamber; means for supplying said ring gear with oil, said oil falling from said ring gear; means for intercepting said oil falling from said ring gear and delivering same to said bearing, said oil then flowing from said bearing to said oil channel; and hold-down means for said table outside said chamber.
35. 12. In a rotary machine of the type employed in the drilling of oil wells, the combination of: a base having an annular oil channel; a rotary table above said base and cooperating therewith to form a closed chamber in which said oil channel is located; a bearing in said chamber adjacent said oil channel for rotatably supporting said table; a ring gear on said table within said chamber; means for supplying said ring gear with oil, said oil falling from said ring gear; a pan in said chamber below said ring gear for intercepting said oil falling from said ring gear and delivering same to said bearing, said oil then flowing from said bearing to said oil channel; and hold-down means for said table outside said chamber.
40. 13. In a rotary machine of the type employed for drilling oil wells, the combination of: a base having an annular oil channel; a bearing supported by said base inwardly of said oil channel and being at a higher level than said oil channel; a rotary table supported by said bearing; means for delivering oil to said bearing from a level above the oil level in the oil channel; and walls forming an oil passage for delivering said oil from the inner part of said bearing downwardly to said oil channel.
45. 14. In a rotary machine of the type employed for drilling oil wells, the combination of: a base having an annular oil channel; a bearing supported by said base inwardly of said oil channel, there being a space inwardly of said bearing; a rotary table supported by said bearing; means for delivering oil to said bearing; and walls forming an oil passage connected to said space inwardly of said bearing and to said oil channel and extending beneath said bearing for delivering said oil from the inner part of said bearing to said oil channel.
50. 15. In a rotary machine of the type employed for drilling oil wells, the combination of: a base having an annular oil channel; a bearing supported by said base inwardly of said oil channel; a rotary table supported by said bearing and having an extension which is surrounded by said bearing, there being an annular space inwardly of said bearing; means for delivering oil to said bearing, said oil flowing through said bearing into said space; and walls on said base forming an oil passage connected to said space inwardly of said bearing and to said oil channel, and extending beneath said bearing for delivering said oil from the inner part of said bearing to said oil channel.
55. 16. In a rotary machine of the type employed for drilling oil wells, the combination of: a base having an annular oil channel; a bearing supported by said base inwardly of said oil channel; a rotary table supported by said bearing and having an extension which is surrounded by said bearing, there being an annular space inwardly of said bearing; means for delivering oil to said bearing, said oil flowing through said bearing into said space; walls on said base forming an oil passage connected to said space inwardly of said bearing and to said oil channel and extending beneath said bearing for delivering said oil from the inner part of said bearing to said oil channel; and means for throwing oil from said extension into said space.
60. 17. In a rotary machine of the type employed for drilling oil wells, the combination of: a base having an annular oil channel, a bearing supported by said base inwardly of said oil channel; a rotary table supported by said bearing; a ring gear on said table; means for delivering oil to said ring gear, said oil falling downwardly from said ring gear; means for intercepting said falling oil and delivering same to said bearing; and walls forming an oil passage for delivering said oil from the inner part of said bearing to said oil channel.
65. 18. In a rotary machine of the type employed for drilling oil wells, the combination of: a base having an annular oil channel; a bearing supported by said base inwardly of said oil channel, there being a space inwardly of said bearing; a rotary table supported by said bearing; a ring gear on said table; means for delivering oil to said ring gear, said oil falling downwardly from said ring gear; means for intercepting said falling oil and delivering same to said bearing; and walls on said base forming an oil passage connected to said space inside said bearing and to said oil channel and extending beneath said bearing for delivering said oil from the inner part of said bearing to said oil channel.
70. 19. In a rotary machine of the type employed for drilling oil wells, the combination of: a base having an annular oil channel; a bearing supported by said base inwardly of said oil channel; a rotary table supported by said bearing and

- having an extension which is surrounded by said bearing, there being an annular space inwardly of said bearing; a ring gear on said table; means for delivering oil to said ring gear, said oil falling downwardly from said ring gear; means for intercepting said falling oil and delivering same to said bearing, said oil flowing through said bearing into said space; and walls on said base forming an oil passage connected to said space inwardly of said bearing and to said oil channel and extending beneath said bearing for delivering said oil from the inner part of said bearing to said oil channel.
20. In a rotary machine of the type employed for drilling oil wells, the combination of: a base having an annular oil channel; a bearing supported by said base inwardly of said oil channel; a rotary table supported by said bearing and having an extension which is surrounded by said bearing, there being an annular space inwardly of said bearing; a ring gear on said table, means for delivering oil to said ring gear, said oil falling downwardly from said ring gear; means for intercepting said falling oil and delivering same to said bearing, said oil flowing through said bearing into said space; walls on said base forming an oil passage connected to said space inwardly of said bearing and to said oil channel, and extending beneath said bearing for delivering said oil from the inner part of said bearing to said oil channel; and means for throwing oil from said extension into said space.
21. In a rotary machine of the type employed for drilling oil wells, the combination of: a base having an annular oil channel; a bearing supported by said base inwardly of said oil channel; a rotary table supported by said bearing; a ring gear on said table; means for delivering oil to said ring gear, said oil falling downwardly from said ring gear; a removable pan means for intercepting said falling oil and delivering same to said bearing; and walls forming an oil passage for delivering said oil from the inner part of said bearing to said oil channel. 5
22. In a rotary machine of the type employed for drilling oil wells, the combination of: a base having an annular oil channel; a bearing supported by said base inwardly of said oil channel; a rotary table supported by said bearing and having an extension which is surrounded by said bearing, there being an annular space inwardly of said bearing; a ring gear on said table; means for delivering oil to said ring gear, said oil falling downwardly from said ring gear; a removable pan means for intercepting said falling oil and delivering same to said bearing, said oil flowing through said bearing into said space; and walls on said base forming an oil passage connected to said space inwardly of said bearing and to said oil channel and extending beneath said bearing for delivering said oil from the inner part of said bearing to said oil channel. 10 20 25 30

DAVID M. SMITH.
